CLAIM

I claim the ornamental design for a hand-held implement for scraping and hammering, as shown and described.

DESCRIPTION

FIG. 1 is a rear isometric view of the hand-held implement for scraping and hammering;

FIG. 2 is a right side elevation view of the hand-held implement for scraping and hammering;

FIG. 3 is a left side elevation view of the hand-held implement for scraping and hammering;

FIG. 4 is a back view of the hand-held implement for scraping and hammering;

FIG. 5 is a front view of the hand-held implement for scraping and hammering;

FIG. 6 is a top view of the hand-held implement for scraping and hammering; and,

FIG. 7 is a bottom view of the hand-held implement for scraping and hammering.
